Altijss.

UNITED STATES PATENT OFFICE

2,498,404

LOOSE-LEAF BINDER

James A. Erwin, Oak Park, Ill.

Application December 21, 1945, Serial No. 636,292

2 Claims. (Cl. 129—24)

1

This invention relates to a loose leaf binder and its principal object is to provide means whereby the binder may be freely and readily opened to enable the leaves to be secured thereto or removed therefrom and which when closed effectively binds the leaves within the covers of the book in which the leaves are bound.

Another object is to provide a loose leaf binder of simple and substantial form, which can be manufactured at a relatively low cost.

Another object is to provide a loose leaf binder which can be completely assembled as a unit and thereafter fixedly secured to the book covers.

With these and other objects and advantages in view, this invention consists in the several novel features hereinafter fully set forth and more particularly defined in the appended claims.

The invention is clearly illustrated in the drawing accompanying this specification, in which:

Fig. 1 is a loose leaf binder embodying a simple form of the present invention, secured to a book cover and having leaves secured to the binder;

Fig. 2 is a cross section taken on the line 2—2 of Fig. 1;

Fig. 3 is an enlarged fragmental cross section taken on the line 3—3 of Fig. 1;

Fig. 4 is an enlarged fragmental cross section taken on the line 4—4 of Fig. 1 and showing the binder open, and

Fig. 5 is a fragmental plan of a slight modification.

Referring to said drawing which is merely illustrative of one embodiment of the invention, the reference character 5 designates a book cover, desirably of the flexible type, comprising two covers 6—6 connected by a flexible back 7.

Secured to the back 7 as by rivets 8 or otherwise is the supporting member 9, preferably comprising a trough-like metal strip, notched and curled up along one edge to provide a plurality of spaced hinge ears 10.

A clasp member 11, somewhat semi-cylindrical in form, is notched and curled up along one edge to provide hinge ears 12 which extend between the hinge ears 10. A hinge pin 13 extends through the hinge ears 10 and 12 and hingedly connects the clasp member 11 to the supporting member 9. The hinge pin is secured to the clasp member by any suitable means and it is here shown as secured to one of the hinge ears 12 of the clasp member by a pin 14 extending through

2

the hinge ear and being upset at its ends to prevent it from coming loose.

One or more coiled tension springs 15 surround the hinge pin 13, two of the hinge ears being made shorter than the others to make room for the springs. One of the arms 16 of each spring engages behind the supporting member 9 and the other arm 17 of each spring engages the outer side of the clasp member. The tension of the springs functions to urge the clasp member into its closed position as seen in Figs. 1, 2 and 3.

On one end of the hinge pin 13 is formed a flattened finger piece 18 which normally lies between and substantially parallel with the book covers. The finger piece may be formed as a part of the clasp member as shown at 18a in Fig. 5.

The clasp member is formed with a plurality of substantially aligned semi-circular spaced fingers 19, the free ends of which are held in close overlapping contact with the supporting member 9 by the coiled springs. The hinge side of the clasp member is formed with a connecting strip 22 which connects the hinge ears 12 with the fingers 19.

The leaves 20 are provided with perforations 21 adjacent one edge in the conventional manner, through which the fingers 19 extend and bind the leaves within the book cover.

To open the binder, the finger piece 18 is swung upward from the position seen in Fig. 3 to that shown in Fig. 4, thereby swinging the fingers away from the supporting member, and disengaging the leaves from the fingers 19. The leaves may then be removed and new leaves placed upon the fingers as seen in Fig. 4. To close the binder on the leaves, the finger piece 18 is released permitting the coiled springs to swing the fingers into engagement with the supporting member, thereby locking the leaves to the binder. With the present loose leaf binder, the leaves may lie flat on the book covers at either side of the binder.

From the above it is apparent that I have provided a loose leaf binder which is easy to open and close, and which effectively binds the leaves in the book cover. It is composed of few parts, easily assembled and not likely to get out of order under ordinary usage. The present binder can be manufactured at a greatly reduced cost as compared with the loose leaf binders now on the market.

Having thus described my invention, it is obvious that various immaterial modifications may

be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a loose leaf binder of the class described having a flexible back and two covers which fold upon themselves with the flexible back centrally thereof to form a book, an integral transversely inwardly curved elongated troughlike supporting member for attachment with its convex face to the concave side of the flexible back of said binder inside thereof, said integral troughlike supporting member forming a straight longitudinally extending edge which faces the inside of one of said covers adjacent one longitudinal margin of said flexible back and forming a plurality of longitudinally spaced hinge ears which face the inside of the other cover adjacent the other longitudinal margin of said flexible back, an elongated integral clasp member comprising a longitudinally extending connecting portion forming a plurality of longitudinally spaced hinge ears for axial coacting alignment with corresponding hinge ears of said supporting member and also forming a plurality of outwardly curved fingers which are adapted to extend through perforations in leaves to be inserted and removably held in said binder, a hinge pin extending through the axially aligned hinge ears of said integral supporting member and of said integral clasp member, respectively, and coiled spring means carried by said hinge pin, the free ends of said spring means engaging portions of said clasp member and of said supporting member, respectively, for urging the free ends of the fingers formed by said clasp member against said supporting member at the straight edge thereof.

2. In a loose leaf binder of the class described having a flexible back and two covers which fold upon themselves with the flexible back centrally thereof to form a book, an integral transversely inwardly curved elongated troughlike supporting member for attachment with its convex face to the concave side of the flexible back of said binder inside thereof, said integral troughlike supporting member forming a straight longitudinally extending edge which is elevated from the inside

surface of the corresponding portion of said flexible back and which faces the inside of one of said covers adjacent one longitudinal margin of said flexible back and forming a plurality of longitudinally spaced hinge ears which face the inside of the other cover adjacent the other longitudinal margin of said flexible back, an elongated integral clasp member comprising a longitudinally extending transversely curved connecting portion forming a plurality of longitudinally spaced hinge ears for axial coacting alignment with corresponding hinge ears of said supporting member and also forming a plurality of outwardly curved fingers which are adapted to extend through perforations in leaves to be inserted and removably held in said binder, a hinge pin extending through the axially aligned hinge ears of said integral supporting member and of said integral clasp member, respectively, said hinge pin being keyed to said clasp member, coiled spring means carried by said hinge pin, the free ends of said spring means engaging portions of said clasp member and of said supporting member, respectively, for urging the free ends of said fingers formed by said clasp member into overlapping engagement with the elevated straight edge of said supporting member, and lever means keyed to said hinge pin for rotating said clasp member relative to said supporting member to place the free ends of the fingers of said clasp member into open position relative to the elevated straight edge of said supporting member.
